ATTORNEY

UNITED STATES PATENT OFFICE.

CHARLES S. JOHNSON, OF MARCY, NEW YORK.

KNIFE-CLIP.

1,268,251.

Specification of Letters Patent.

Patented June 4, 1918.

Application filed February 21, 1914. Serial No. 820,329.

To all whom it may concern:

Be it known that I, CHARLES S. JOHNSON, a citizen of the United States, residing at Marcy, in the county of Oneida and State of New York, have invented certain new and useful Improvements in Knife-Clips, of which the following is a specification, reference being had therein to the accompanying drawing.

10 My invention relates to a knife clip and I declare the following to be a full, clear, concise, and exact description thereof sufficient to enable any one skilled in the art to which it appertains to make and use the same, reference being had to the accompanying drawings in which like reference characters refer to like parts throughout the specification.

The object of the invention is to provide a knife clip that will be of simple construction and adapted to permit the quick and easy detachment of the cutter bar and cutting knives or plates connected thereto from its channel adjacent the finger bar of a mowing machine. Such a clip will be found of inestimable value in view of the clip that has been heretofore employed in the art, which clip is bolted to the cutter bar and guard and in order to serve its function properly, its end is hammered down against the surface of the cutting knife or plate. The hammering of the end of the clip tends to throw its lower surface out of alignment with the lower surface of the ends of the other clips, also hammered, and thereby prevent the easy detachment of the cutter bar and cutting knives or plates connected thereto, when the knife edges of the cutting knives or plates need grinding or sharpening. The troublesome feature just referred to is avoided in applicant's invention, as will be observed by referring to the accompanying drawings, in which Figure 1 is a plan view of a cutter bar and immediate parts;

45 Fig. 2 is an enlarged perspective view of a member employed;

Fig. 3 is an enlarged perspective view of a fragment of the cutter bar and immediate parts;

50 Fig. 4 is an enlarged perspective view of the locking mechanism, showing a part cut away, on the line 4-4 of Fig. 3;

Fig. 5 is an enlarged perspective view, partly in section, of a casing and wedge

shaped member employed; showing the 55 parts in abnormal position, or with the spring under pressure;

Fig. 6 is an enlarged plan view of a modified manner of holding the wedge shaped member in normal position.

Referring more particularly to the drawings, the parts of the machine that are old and well known in the art, are the finger bar 1, the guards 2, having secured thereto the plates 3 serrated at 4, the cutter bar 5 upon which is mounted the cutter knives or plates 6, and the tedder 30.

The novel feature of the invention comprises the mechanism adapted for detachably holding the cutter bar 5 and the cutting plates 6 connected thereto, in its channel 7 formed by the recessed parts 8 and the lugs 9 of the guards 2. The mechanism embodies a plurality of the plates 14 disposed upon the finger bar 1. Upon the plates 14 rest the plates 10 having reduced portions 11-11 with apertures 12-12, which are countersunk for the flush fitting of the heads of the bolts 13-13 that pass therethrough and through the aligned holes in the plates 14 and in the finger bar 1, whereby they may secure the guards 2 in assembled position upon the finger bar 1, as is well known in the art. The plates 14 are made separate from the plates 10, although they may be 85 made integral therewith. The elevated central portion 15 of the plate 10 has an interior recess 16 provided with the sides 17 that taper in a longitudinal manner. The sides 17 are, furthermore, arranged with the teeth 18 adapted to mesh with the teeth 19 of the members or arms 20, pivotally connected at 21. The teeth 19 of the members 20 are held in mesh with the teeth 18 of the sides 17 of recess 16 by the wedge shaped member 22, 90 that is held yieldingly in normal position, as illustrated in Fig. 4, by the spring 23, coiled about the spindle 24, secured to the wedge shaped member 22. The spring 23 bears at one end against the flange 25 of the casing 26, and at its other end against the boss 27 mounted to the end of the spindle 24. The casing 26 is held stationary upon the bottom surface of the recess 16 of the plate 10 by the screw or bolt 28 passing through 105 the aperture 29 of the casing 26 and into the bottom surface of the plate 10. The wedge shaped member 22 is provided with a

recess 31 for the reception of the adjacent end of the casing 26, when the said member 22 is resting in its normal position, as seen in Fig. 4, and a handle 32, whereby the member 22 may be moved rearwardly to free the contiguous ends of the members 20, when the operator desires to remove the members 20 from the recess 16. The sides 33—33 of the members 22 are tapered to aid in separating the free ends of the members 20 when assembling the same. The outer ends of the members 20 are disposed in horizontal position, so as to lie parallel with the upper surfaces of the cutting plates 6 and to thereby hold the cutting plates 6 tightly against the plates 4 upon the guards 2, so that the knife edges 34 of the cutting plates 6 will effectively coöperate with the serrated edges 4 of the plates 3 to cut the grass. Furthermore, the members 20 are arched at 35 to provide a clearance for the top portions of the rivets 36 that secure the cutting plates 6 to the cutter bar 5. The members 20 are also shouldered at 37 to form stops adapted to abut against the surface or edge of the recess 16 formed in the elevated portion 15 of the plate 10, whereby to limit the inward projection of the members 20, when the same are being disposed in locked position.

The operation of the device is effected by employing any number of the locking members that are secured at suitable intervals along the finger bar 1. The cutter bar 5 with its cutting plates 6 is assembled in its channel 7, in such a manner that the ends 40 of the cutting plates 6 will ride normally along the surfaces of the plates 14, and the bar 5 and the plates 6 free to slide or reciprocate under the action of a pitman, not here shown, secured at the end 45 of the cutter bar 5, by inserting, as far as the shoulders 37 will permit, the free ends of the members 20 into the recess 16 of the elevated portion 15 of the plate 10. The free ends of the members 20 will ride over the tapered sides 33 of the wedge shaped member 22 and come to rest against the sides 41—41 of the said member. In this position, the teeth 19 of the members 20 will mesh with the teeth 18 of the sides 17 of the recess 16, whereby to hold the members 20 in locked position. In the event, that it is found desirable to remove the cutter bar 5 in order to sharpen the knife edges 34 of the cutting plates 6, the operator pulls outward on the handles 32 to draw the members 22 rearwardly and free from the contiguous ends of the members 20, whereupon, the free ends of the members 20 may be moved toward each other, so that the teeth 19 of the members 20 will clear the teeth 18 of the sides 17 of the recess 16, and thus permit the removal of the members 20 from the recesses 16. The cutter bar 5 with its cutting plates 6 may be then withdrawn lat-

erally from the channel 7 and taken from the machine. Upon releasing the handles 32, the wedge shaped members 22 will move forward under the tension of the springs 23 into their normal positions, as shown in Fig. 4, whereby to again be in the location to lock the free ends of the members 20, when they are returned to the recess 16.

Fig. 6 shows a modified manner of returning the wedge shaped member 22 to its normal position. The means embodies a coiled spring 50 secured at one end to an orifice 51 in the member 22 and at the other end to a hook or inverted U shaped member 52 secured to the bottom of the recess 16 of the plate 10 at about the location of the bolt 28 of the former construction. The member 22 is held to a given path of movement by the spindle 53, secured to the said member 22 and projecting through the interior of the coiled spring 50.

Having thus described my invention what I claim as new and desire to secure by Letters Patent is:

1. In a mowing machine having a cutter bar, a plate, to be mounted on a finger bar, having a recess, removable means mounted in said recess for holding said cutter bar in position, and spring means for holding said removable means in place.

2. In a mowing machine having a cutter bar, a plate, to be mounted on a finger bar, having a recess, two arms pivoted at the front of said plate and extending downwardly upon said cutter bar, and spring means for holding said arms in position in said recess.

3. In a mowing machine having a cutter bar, a plate, to be mounted on a finger bar, having a recess, two arms pivoted at the front of said plate and extending downwardly upon the cutter bar, and detachable means for holding said arms in said recess in said plate.

4. In a mowing machine having a cutter bar, a plate, to be mounted on a finger bar, having a recess, two arms pivoted together, teeth in said arms, other teeth in said plate, and spring means, whereby to hold said arms within the recess in said plate.

5. In a mowing machine having a cutter bar, a plate, to be mounted on a finger bar, having a recess on its lower side, teeth formed within said recess, two arms pivoted at the front of the plate, and extending downwardly upon the cutter bar, and teeth on said arms, whereby to engage with the first mentioned teeth, within said recess, and means for holding the teeth in said arms in mesh with the teeth in said recess.

6. In a mowing machine having a cutter bar, a plate, to be mounted on a finger bar, having a recess, teeth formed in said plate, two arms pivoted at the front of the plate and extending downwardly upon the cutter bar.

bar, teeth formed on the opposite ends of said arms, whereby to engage with the teeth formed in said plate, and a wedge shaped member, having a handle, located in the recess in said plate, and spring means for holding said teeth on said arms in mesh with the teeth formed in said plate.

In testimony whereof I have affixed my signature in the presence of two witnesses.

CHARLES S. JOHNSON.
